By his Attorneys,

James L. Kerstetter *Inventor.*

C. Howes.

UNITED STATES PATENT OFFICE.

JAMES L. KERSTETTER, OF BRADFORD, PENNSYLVANIA.

DESIGN FOR A WRITING-TABLE CABINET.

SPECIFICATION forming part of Design No. 28,262, dated February 8, 1898.

Application filed December 31, 1897. Serial No. 665,239. Term of patent 3½ years.

To all whom it may concern:

Be it known that I, JAMES L. KERSTETTER, a citizen of the United States, residing at Bradford, in the county of McKean and State 5 of Pennsylvania, have invented a new and original Design for a Combination Writing-Table Cabinet, of which the following is a specification.

This invention relates to a new and original 10 design for a combination writing-table cabinet; and it has for its object to provide a design of this character that shall be both useful and ornamental.

The leading feature of the design resides 15 in an upright cabinet-body having narrow forwardly-convergent side walls meeting the side edges of the front wall in an obtuse angle, said front wall being provided at a point near its lower end with a forwardly-projected horizontal- 20 pen-rack shelf-piece and a flat rectangular base-piece arranged at the lower end of the cabinet-body and having its end portions projected beyond the side walls of said body.

A minor feature of the design is to provide 25 the front and side walls of the cabinet-body with plain rectangular panels and to arrange at the top edges of the cabinet-body scrolled edging-strips and a pair of short post-like ornaments, said post-like ornaments being 30 provided with rounded top portions and arranged in line with the meeting-points between the front and side walls of the cabinet- body.

In the drawings, Figure 1 is a perspective 35 view of a writing-table cabinet embodying the herein-described design. Fig. 2 is a front elevation thereof.

Referring to the accompanying drawings, the numeral 1 designates an upright cabinet- 40 body having narrow forwardly-convergent

side walls meeting the side edges of the vertical front wall in an obtuse angle. The narrow side walls of the cabinet-body are each provided with a single rectangular plain panel 2, extending nearly the entire length thereof, 45 while the vertical front wall of the cabinet is provided with separate rectangular panels 3 and 4, respectively, of different sizes. Immediately below the plain larger panel 3 of the front wall of the cabinet-body said front wall 50 is further provided with a forwardly-projecting horizontal pen-rack shelf-piece 5, having sigmoidally-curved end edges 6 and a longitudinal concavity 7 in its upper side.

The upright cabinet-body 1 is surmounted 55 at its top edges by scrolled edging-strips 8 and a pair of short post-like ornaments 9, arranged in line with the meeting-points between the front and side walls of the cabinet- body and provided with rounded top portions 60 10.

The upright cabinet-body 1 is arranged on top of a flat rectangular base-piece 11, which is provided with beveled or molded edges 12 and has its end portions project beyond the 65 plane of the narrow side walls of the cabinet- body. The projecting end portions of the flat base-piece 11 are provided in their upper faces with surface ink-well depressions or concavities 13. 70

What I claim is—

The design for a writing-table cabinet, herein shown and described.

In testimony that I claim the foregoing as my own I have hereto affixed my signature in 75 the presence of two witnesses.

JAMES L. KERSTETTER.
